UNITED STATES PATENT OFFICE

HARRY A. MONTGOMERY, OF BALTIMORE, MARYLAND.

PORTABLE TESTING APPARATUS FOR WATER-DISTRIBUTING SYSTEMS OF RAILWAY PASSENGER-CARS.

1,353,810.

Specification of Letters Patent. Patented Sept. 21, 1920.

Application filed January 14, 1920. Serial No. 351,296.

To all whom it may concern:

Be it known that I, HARRY A. MONTGOMERY, a citizen of the United States of America, and a resident of the city of Baltimore, State of Maryland, have invented certain new and useful Improvements in Portable Testing Apparatus for Water-Distributing Systems of Railway Passenger-Cars, whereof the following is a specification.

10 In railway passenger cars of the Pullman type and others of modern construction, the water for supplying the basins and water closets is maintained and distributed under air pressure from a tank beneath the car, the compressed air being obtained from the train brake apparatus when the car is connected in train and from the station air plant when the car is detached from the train and stalled in the station or yard. The 15 air pressure of the station airplant and of the brake system being at a high point, usually one hundred and ten pounds to the inch, sufficient to supply the air cylinders of the air brake system, must be reduced before it can be utilized in the water tank. The usual air system for the water tank includes a governor valve and a reducing valve. The governor valve receives the air on its inlet side of the high pressure of the 20 brake system and delivers it on the outlet side toward the air reservoir of the water distributing system at a pressure not to exceed fifty or sixty pounds, and governs the passage of air from the auxiliary air reservoir of the brake system to the air pressure reservoir which furnishes air pressure to the water tank. The reducing valve reduces the pressure of the air brake system to the requirements of the water distribution. Frequent testing of these valves is necessary 25 in order to determine whether or not they are in proper working condition.

The object of this invention is to provide a simple portable apparatus adapted for 30 testing the governor valve and the reducer valve of individual cars without removal thereof from the system. In case said valves or either of them are found defective then only are they detached from the system and properly adjusted or corrected. This apparatus also provides means for testing the corrected valves at the car to ascertain whether or not they are properly adjusted before restoration to the system, avoiding

the necessity of taking them to the shop 55 for such testing. In this way time is saved, and delay of trains avoided.

Figure 1 of the accompanying drawings represents diagrammatically this testing apparatus in its preferred form of embodiment, connected up with the water supply system of a car.

Fig. 2 represents a plan view of this testing apparatus on an enlarged scale detached from the car equipment and showing 65 a governor valve in position to undergo the secondary test thereof after correction of defects and preparatory to replacement in the system.

Fig. 3 represents a side elevation of the 70 apparatus showing the reducer valve detached from the car equipment and in position on the tester for undergoing the secondary test.

Fig. 4 represents a transverse section of 75 the tester on line 4-4 of Fig. 3.

Fig. 5 represents on an enlarged scale 80 a longitudinal section of a retarding device for preventing a sudden pressure from the high pressure side exerting undue impulse on the gage.

Fig. 6 represents a transverse section on line 6-6 of Fig. 3.

Similar reference characters indicate corresponding parts in the different figures. 85

In Fig. 1 is shown the usual arrangement of the water distribution system of Pullman cars and of modern railway coaches, including the Westinghouse governor valve and the reducing valve. In the passenger 90 car equipment this water distribution system comprises a water tank A from which the water is supplied under a determinate air pressure to the toilet rooms of the car, an air pressure reservoir B having a pressure 95 gage b, a pipe C connecting said reservoir with said tank, an air supply pipe D connected at its inner end with said pipe C and adapted for connection at its outer end with the source of supply, and an auxiliary 100 air reservoir E of the brake system connected by pipe F with the supply pipe D through the strainer D' thereof. A governor valve G is disposed in the pipe D between the auxiliary reservoir E and the air 105 pressure reservoir B, and a reducing valve H is disposed in the pipe C between the connection therewith of the pipe D and the wa-

ter tank A. A five-way cock I is disposed in the pipe C adjacent to the water tank and is provided with ports and connections for the water supply to the tank and for the 5 water delivery from the tank and for the escape of air from the tank when desired. The pipe C is provided with a check valve J, with a stop cock K and with a gage L disposed between the connection of the air 10 supply pipe D and the air pressure water tank A, with a stop cock M between said tank A and the five-way cock I and with a stop cock N between the connection of said pipe D and the air pressure reservoir B. These 15 stop cocks are open when the actuating handles are disposed in transverse relation to the pipe.

The governor valve G is set to be actuated at a predeterminate pressure of usually not 20 less than fifty or sixty pounds. The reducing valve H is usually adjusted to deliver twenty-two pound pressure on the water in the water tank for forcing it throughout the car. Necessary adjustments of this valve 25 are made by the nut at the top thereof.

The foregoing lettered description relates to parts of the car equipment which are old and well known and constructive details thereof are not herein necessary. An 30 example thereof is illustrated in the catalogue of Westinghouse Air Brake Company in Part Catalogue No. 3217-1 of December 1910.

This testing apparatus for determining 35 whether or not the governor valve and reducing valve hereinbefore referred to are in proper condition consists of a portable device comprising a main pipe 10 provided at one end with a coupling member 11 adapted to be connected with the air-hose of a station air plant or of the train system and at the other end with a coupling member 12 adapted to be connected with the air supply pipe D of the water distribution system 40 of an individual car. This pipe has a stop cock 13 which is normally open, the open position of the actuating handle being transverse to the pipe in reverse of the usual construction.

45 A testing reducing valve 20 is mounted in the pipe 10. This testing reducing valve is of the same construction as the governor valve G of the water distribution system and is set to operate at a lower pressure than said system governor valve, the testing reducing valve being at forty-five degrees whereas the system governor valve is set at fifty degrees. This pipe 10 and its reducing valve 20 are utilized in testing the governor 50 valve of the car when in position in the water distribution system as hereinafter described.

A by-pass pipe 30 extends substantially parallel with the main pipe 10 and a lateral pipe 31 is connected at one end with said

main pipe between the stop cock 13 and the testing reducing valve 20 and at its other end with said by-pass pipe near its rear end. A transverse pipe 32 is connected at its off end with the front end of said by-pass pipe and a downward pipe 33 connects said transverse pipe 32 with the main pipe 10 in front of the testing reducing valve 20. A valve 34 in the off end of said pipe 32 is operative to close communication 70 between the by-pass pipe 30 and the transverse pipe 32. An upward elbow extension 35 is connected with the near end of the transverse pipe 32 and carries a four-way coupling 39 to which is attached a pressure 75 gage 36 and a blow off cock 37 therefor. A four-way coupling 38 connects the pipes 32, 33 and 35 and another hereinafter described.

A retarding device 40 is mounted in the 80 by-pass pipe 30. This retarder comprises coupled members 41 and 42 carrying an intervening disk 43 provided with a minute port 44, through which the air is made to pass. The purpose of this retarder is to 85 prevent shock and injury to the gage by preventing high tension air from the source of supply coming suddenly in contact with the gage. In other words this retarder permits the air to pass through slowly so as 90 to build up the pressure gradually on the farther side thereof.

A short test tube 50 is mounted in the coupling 39 at the upper end of the elbow pipe 35 and extends rearward therefrom. 100 This test tube is provided with a stop cock 51 and at its rear end with a coupling 52 adapted to receive a system governor valve G for testing. The by-pass pipe 30, the test tube 50 and the intermediate connections just hereinbefore described, are employed as hereinafter described in testing 105 the governor valve G when detached from the system.

A test tube member 60 for a detached reducing valve H is connected by a double elbow pipe 61 with the upper branch of the four-way coupling 38 and extends rearward substantially parallel with the by-pass pipe 30 with which it cooperates. This test tube 110 member is provided with a stop cock 62 and at its rear end with a coupling 63 adapted to receive one side of the reducing valve to be tested. The by-pass pipe 30 in rear of the lateral connecting pipe 31 is provided 115 with a stop cock 64. This by-pass pipe has at its rear end an upward extension 65 which is connected by an elbow 66 with a forward extending test member 67, which carries a coupling 68 adapted to receive the 120 other side of the reducing valve to be tested. The by-pass pipe 30, test tube member 60, test tube member 67 and the connecting elements just hereinbefore described are employed as hereinafter described in testing 125 130

a reducing valve H when detached from the system.

The use of this testing apparatus in its various ways for testing the governor valve G while in position in the system, for testing the reducing valve H while in situ in the system, for testing the governor valve G after removal and correction of any error discovered in the testing aforesaid and preliminary to its restoration to the system, and for testing the reducing valve when detached from the system after correction of any error that may have been discovered by the testing in situ and preparatory to its restoration to the system, will now be described. The most convenient way of performing the test is to first test the governor valve in situ in the system, then the reducer valve in situ in the system and thereafter make the individual tests of either or both if necessary; but the claims are not to be construed as limited to any particular order of making the tests.

For testing the governor valve G while in situ in the system the testing apparatus is prepared for connection with the system by closing the stop cock 13, the valve 34, the stop cock 51, the stop cock 62 and the stop cock 64, and the testing reducing valve 20 is set to permit the air which enters it at the left at a pressure of one hundred and ten, more or less, to pass out at a pressure not exceeding forty-five pounds to the inch. The coupling member 11 of the main pipe 35 10 is then connected with the coupling member of the air hose of a station airplant or other source of air under pressure and the coupling member 12 of said pipe is coupled with the air supply pipe D of the water distribution system of an individual car. Then the five-way cock I is turned so as to permit the expulsion of air from the water tank A and air pressure reservoir B so that there is then no pressure in the water supply system 40 beyond the governor valve G. Then the stop cock 13 is opened and the air comes in through the pipe 10 at a pressure or ninety to one hundred and ten pounds to the inch on the inlet side of the testing reducing valve 20, passes through said valve and out at the outlet side thereof at a pressure of forty five pounds, but such pressure will not affect the governor valve G in the car if it be in operative condition; being set at 45 fifty pounds pressure, it will remain closed and no air will pass it. But if the car valve G be wrongly set for a lower pressure or if it be leaky through defect or the presence of a cinder so as to reduce its capacity of 50 resistance below 45, more or less air will pass said car valve G and will create pressure in the system beyond said valve, and such pressure will be indicated on a gage b of the air pressure reservoir B or the gage L in 55 any place in the system on the delivery side

of the governor valve G. A watchful wait of about five minutes will determine whether or not air has passed through the governor valve G in quantity sufficient to be indicated on the gage. If so the valve is defective and must be removed for cleaning, removal of cinders, resetting, renewal of parts or other repairs.

After such cleaning or repairing and adjusting of the valve G for a pressure of fifty pounds, it becomes necessary to determine whether or not it is in perfect condition and whether or not the adjustment is correct. This testing of the detached governor valve can be done without taking it to the shop by simply connecting it up with the test tube 50 of the testing apparatus. Then the stop cock 51 is opened and the valve 34 remaining closed the pressure delivered to the governor G corresponds with the pressure on the delivery side of the reducing valve 20, which is at forty five pounds. Then the operator places his thumb at the orifice of the free side of the governor valve and if he feels any air escaping or hears a hissing sound thereof, it is evident that the governor G is defective or set at too low a point. Then the cap thereof is removed from the governor valve and said valve is readjusted to a higher pressure. Then the valve 34 is opened and air at a higher pressure than that which passes through the reducing valve 20 is permitted to pass around through the by-pass pipe 30 and its connections through the test tube 50 to the governor. The retarder 40 permits this high pressure air to pass around slowly so as not to shock the gage 36 and the air so passed around gradually builds up pressure in the pipes on the off side of said retarder, which pressure is indicated on the gage 36 and correspondingly impressed on the governor G in the test tube 50. The operator watches said gage and when it indicates a pressure of fifty degrees he manipulates said governor G and adjusts it to correspond to that pressure. Then the governor is detached from the testing apparatus and replaced in the system in the car ready to do its duty again.

For testing the reducing valve H while in the system, the cock 13 is first opened, the other cocks and valve 34 being closed. The air at high pressure enters through the pipe 10 at the left of the testing reducing valve 20 and passes around through the by-pass pipe 30 to the pipe 10 in front of said testing reducing valve, and gradually builds up an air pressure in the distributing system of the car to a point on the inlet side of the governor valve G in situ in the system corresponding with the pressure of the plant, say ninety to one hundred and ten pounds. As the said governor valve delivers the air at a pressure of fifty pounds,

a pressure of that degree will be built up in the air pressure reservoir B. If the reducing valve H of the system be in proper working condition, air will pass said valve and be delivered at the water tank side thereof at a pressure of twenty two pounds to the inch, which will be indicated on the gage L in the pipe C. If the gage indicates a pressure below or above the desired point of twenty two pounds to the inch, or thereabout, it is defective and must be removed for correction.

After repairing or correcting the system reducing valve H it is mounted in the testing apparatus between the test tube members 60 and 66. The cock 51 is closed, the valve 34 closed and the cocks 13, 62 and 64 are opened. Then the air passes from the pipe 10 through the lateral branch pipe 31 into the by-pass pipe 30, thence through the upward extension 65, elbow 66 and test member 67 into and through the reducing valve H to be tested; thence through the test member 60, through the double elbow pipe 61, the four-way coupling 38, through the downward pipe 33 from said coupling into the pipe 10 in front of the reducing valve 20 and thence into the car hose which is connected with the coupling 12. The car hose acts as a reservoir in which to build up back pressure, the angle cock (not shown) in the car which closes said hose to the interior pipe system being shut off. The back pressure as it is built up is indicated on the gage 36. As soon as a pressure of twenty-two pounds to the inch is registered it is evident that the reducing valve is correct. If the pressure on the gage is in excess of or below twenty two pounds or other desired setting of said reducing valve H said valve is readjusted until its proper passing pressure is indicated on the gage. This is done by removing the cap and adjusting the tension screw of the reducing valve in a manner well known to those skilled in the art. When these tests show through the gage 36 a proper working condition of the reducing valve H it is removed from the testing apparatus and replaced in its proper position in the car equipment and the work is completed.

This invention is not limited to the particular embodiment hereinbefore described; on the contrary it includes various embodiments and variations of parts within the scope of the following claims.

I claim as my invention:

1. A portable combined situ and individual testing apparatus for the water supply system of an individual railway car, said apparatus comprising a situ testing means, including a piping, brake hose coupling members, a testing reducing valve and an air gage connected therewith, operative 60 in connection with the system for testing

the governor valve of the system while in situ therein, an individual testing means including an extension connected with said piping and adapted to receive said governor valve for testing when detached from the system, and means adapting said apparatus to perform said testing functions successively.

2. A portable combined situ and individual testing apparatus for the water supply system of an individual railway car, said apparatus comprising a situ testing means including a piping, brake hose coupling members, a by-pass pipe and an air gage connected with said piping, operative in connection with the system for testing the reducing valve of the system while in situ therein, an individual testing means, including tube extensions adapted to receive said reducing valve, for testing said reducing valve when detached from the system, and means adapting said apparatus to perform said functions in succession.

3. A portable combined situ and individual testing apparatus for the water supply system of an individual railway car, said apparatus comprising a situ testing means, including a piping, brake hose coupling members, a testing reducing valve and an air gage connected with said piping, operative in connection with the system while in situ therein, a situ testing means including a by-pass pipe connected with said piping, operative in connection with the system for testing the reducing valve thereof while in situ therein, an individual testing means including an extension connected with said piping and adapted to receive said governor valve for testing when detached from the system, an individual testing means, including tube extensions connected with said piping, adapted for testing said reducing valve when detached from the system, and means adapting said apparatus to perform said functions one after another.

4. A testing apparatus for water distributing systems of railway cars comprising a main pipe provided at its opposite ends with brake house coupling members adapted respectively for connection with the brake hose coupling member of an air supply plant and the brake hose coupling member of the air supply pipe of said water distributing system, a testing reducing valve mounted in said pipe and adapted to receive the high pressure air of an air plant on one side and pass it through at a comparatively low pressure on the other side, and an air gage connected with said pipe on the low side of said testing reducing valve.

5. A testing apparatus for water distributing systems of railway cars comprising a piping provided at its opposite ends with brake hose coupling members respectively adapted for connection with the brake

hose coupling member of the air supply plant and with the brake hose coupling member of the air supply pipe of the water distributing system, a retarder disposed in 5 said piping between said coupling members and adapted to pass the high pressure air entering from the source to the car system, and a gage mounted in said piping.

6. A testing apparatus for water distributing systems of railway cars comprising 10 a main pipe provided at its opposite ends with coupling members adapted respectively for connection with an air supply plant and the air supply pipe of the water distributing system, a testing reducing valve 15 mounted in said pipe and adapted to receive the high pressure air of the air plant on one side and pass it through at a comparatively low pressure on the other side, an air gage 20 connected with said pipe on the low side of said testing reducing valve, and a by-pass pipe connected to said main pipe on opposite sides of said testing reducing valve and provided with a retarder which 25 permits the high pressure air to pass slowly through said by-pass pipe.

7. A testing apparatus for water distributing systems of railway cars comprising a main pipe provided at its opposite ends 30 with coupling members adapted respectively for connection with an air supply plant and the air supply pipe of the water distributing system, a testing reducing valve mounted in said pipe and adapted to receive the high 35 pressure air of the air plant on one side and pass it through at a comparatively low pressure on the other side, an air gage connected with said pipe on the low side of said testing reducing valve, a by-pass pipe connected 40 to said main pipe on opposite sides of said testing reducing valve and provided with a retarder which permits the high pressure air to pass slowly through said by-pass pipe, and a valve for closing communication 45 between said by-pass pipe and said main pipe.

8. A testing apparatus for water distributing systems of railway cars comprising a main pipe provided at its opposite ends with coupling members adapted respectively for 50 connection with an air supply plant and the air supply pipe of the water distributing system, a testing reducing valve mounted in said pipe and adapted to receive the high pressure of the air plant on one side and 55 pass it through at a comparatively low pressure on the other side, a pressure gage connected with said pipe on the low side of said testing reducing valve, a by-pass pipe connected to said main pipe on opposite 60 sides of said testing reducing valve and provided with a retarder which permits the high pressure air to pass slowly through said by-pass pipe, a pipe connected with said by-pass pipe and gage, a stop cock in said 65 last named pipe, and a test tube adapted to

receive one side of a governor valve of said system when detached for secondary testing.

9. A testing apparatus for water distributing systems of railway cars comprising a main pipe provided at its opposite ends with coupling members adapted respectively for connection with an air supply plant and the air supply pipe of the water distributing system, a testing reducing valve mounted 75 in said pipe and adapted to receive the high pressure air of the air plant on one side and pass it through at a comparatively low pressure on the other side, an air gage 80 connected with said pipe on the low side of said testing reducing valve, a by-pass pipe connected to said main pipe on opposite sides of said testing reducing valve and provided with a retarder which permits the high pressure air to pass slowly through 85 said by-pass pipe, a valve for closing communication between said by-pass pipe and said main pipe, and test tube members connected with opposite ends of said by-pass pipe and adapted to receive between them 90 the reducing valve of the car system when detached for secondary testing and cocks for controlling said test tube members.

10. The combination with a water tank for supplying water to the toilet rooms of a railway car, an air reservoir, a pipe connecting said air reservoir and water tank, an air supply pipe connected with said connecting pipe, a governor valve located in 95 said air supply pipe and adapted to receive high pressure air on one side and deliver it at a determinate lower pressure on the other side, a reducing valve located in said connecting pipe and adapted to receive air on its inlet side at the delivery of said governor valve and to deliver it on its outlet side at a lower pressure, a pressure gage on the delivery side of said reducing valve, and a gage between said governor valve and said reducing valve, of a portable apparatus 100 transferable from car to car and comprising a main pipe provided at its opposite ends with coupling members adapted respectively for connection with an air supply plant and with said air supply pipe of said water distributing system, a testing reducing valve mounted in said pipe and adapted to receive the high pressure air of the air plant on one side and pass it through on the other side at a pressure approximating but below 105 the pressure of said governor valve, and an air gage connected with said pipe on the low side of said testing reducing valve.

11. The combination with a water tank for supplying water to the toilet rooms of a railway car, an air reservoir, a pipe connecting said air reservoir and water tank, an air supply pipe connected with said connecting pipe, a governor valve located in 115 said air supply pipe and adapted to receive 120

said air supply pipe and adapted to receive 125

high pressure air on one side and deliver it at a determinate lower pressure on the other side, a reducing valve located in said connecting pipe and adapted to receive air 5 on its inlet side at the delivery pressure of said governor valve and to deliver it on its outlet side at a lower pressure, a pressure gage on the delivery side of said reducing valve, and a gage between said governor 10 valve and said reducing valve, with a portable apparatus transferable from car to car and comprising a piping provided at its

opposite ends with coupling members respectively for connection with a supply plant and the air supply pipe of the water distributing system, a retarder disposed in said piping between said coupling members and adapted to pass the high pressure air entering from the source to the car system, and a gage mounted in said piping. 15
